NAIL CLIPPER

William E. Bassett, Woodbridge, Conn.

Application February 6, 1947, Serial No. 726,785

3 Claims. (Cl. 132—75.5)

1

This invention relates to a clipper for trimming finger nails, toe nails, and the like, particularly the type of clipper comprising a pair of curved cutting jaws normally held in spaced relation, with a pivoted lever for forcing the jaws together for the clipping operation, and has for an object to provide such a device with an improved form of nail file which may be swung outwardly for use and when not in use is covered and protected.

Another object is to provide means on this file for holding the operating lever of the clippers in the inoperative position when not in use.

With the foregoing and other objects in view, I have devised the construction illustrated in the accompanying drawing forming a part of this specification. It is, however, to be understood the invention is not limited to the specific details of construction and arrangement shown, but may embody various changes and modifications within the scope of the invention.

In this drawing:

Fig. 1 is a top plan view of the device on an enlarged scale, showing it in a closed or inoperative condition;

Fig. 2 is a side view;

Fig. 3 is a section substantially on line 3—3 of Fig. 1;

Fig. 4 is a top plan view showing the operating lever swung up from the normal or inoperative position;

Fig. 5 is a side view showing the cutting jaw operating mechanism in the operative position and showing the file swung out to one position of use, and

Fig. 6 is a detail section substantially on line 6—6 of Fig. 1.

This improved clipper comprises two superimposed cutter jaw members 10 and 11 which are preferably stamped from sheet metal of fairly heavy gauge of any desired shape, but preferably of the substantially oblong shape shown, and which are secured in the superimposed relation at one end portion by any suitable means, such, for example, as spot welding 12. These members are provided at their opposite ends with cutter jaws 13 and 14, the free edge portions of which are provided with curved cutting or knife edges 15 and 16 opposed to each other so that when forced together on opposite sides of a finger nail, toenail, or the like, they will trim it to the curved shape of these cutting edges, the free ends of the jaws being preferably inclined toward each other somewhat, as shown in Figs. 2, 5 and 6. These jaws are normally held in separated or spaced relation, as shown in Figs. 2, 5 and 6, and this may

be done by various means, but preferably either one or both of the members 10 and 11 are spring members, or made of resilient metal, which tend to assume this position.

5 The means for operating these jaws and their cutting or knife edges comprises a pin or rivet 7 extending through aligned openings 18 and 19 in the jaws, with its head 20 on the under side of the lower jaw and its shank extending through the upper jaw to a distance above this jaw, this shank being provided in one side with a curved transverse recess or notch providing at its top an inverted curved hook portion 21 in which is seated a transverse bar 22 at the end of an operating lever 23. This bar is provided by cutting an opening 24 in this lever spaced a suitable distance back from its free end, and the free end of the lever is bent downwardly, as shown at 25, to rest against the top of the upper jaw member 11, so that the spring action of the jaws will tend to swing the free end of the lever 23 downwardly against the top of the upper jaw member out of the way into the inoperative position, as shown in Figs. 1 and 2, this action being secured by the 10 lever action on the ends of the curved portion 25, and the bar 22 seating in the hook 21 of the rivet. The lever is also provided with an upwardly pressed lug 26 a short distance from the rivet or pin 7, the free end 27 of which, when 15 the lever is reversed, may rest on the top of the upper jaw member 11 for operation of the cutter in the clipping operation, this position being shown in Fig. 5. In moving this device to this position the lever is raised from the position of 20 Figs. 1 and 2 about its pivot bar 22 to the position of Fig. 4, and then is swung in a circle about the pin 7, the pin during this movement turning in the jaws as a pivot for the lever to permit the lever to be swung to the position of Fig. 5, in which position it is reversed or turned over from the position of Figs. 1 and 2 so that the lug 26 is on the under side of the lever, and its free edge 25 rests on the top of the upper jaw member 11, as shown in Fig. 5, the bar 22 of the lever remaining in the notch 21 of the pin and forming a pivot for the lever. Now, by pressing downwardly the free end of the lever 23, the lug 26 will force the upper jaw member 11 downwardly or toward the other jaw member 10, and will force 30 the cutting or knife edges 15 and 16 together for the clipping or trimming operation. After use, the lever 23 may be swung again to the position of Fig. 4, using the pin 7 as a pivot, and then swung to the inoperative position on top of the jaw member 11 as shown in Figs. 1 and 2. If

desired, the free end 28 of this lever may be tapered and rounded and reduced in thickness to provide a means for cleaning under the finger nail, and on its underside (which is the upper side when the lever is in the position of Figure 5) it may be cut or roughened, as shown at 29, to form a better grip for the thumb when using the device. Also it is preferred that the end portion of this lever be bent downward as shown at 36, Figure 5. This brings the portion 37 between this point and the free end 28 on a plane substantially parallel with the body of the clipper, particularly when the lever is depressed into the position where the cutting edges grip and cut the nail, so that the thumb pressure is exerting a force on the pad rather than on the end of the lever. This bend also raises the free end 28 of the lever above the member 30 when in the folded position of Figure 2 to provide a clearance under this free end as shown at 38 for insertion of a thumb nail to facilitate raising the lever.

Through the opposite ends of the jaw members 10 and 11 is formed an opening whereby the device may be connected to a key ring, chain or the like, and pivotally mounted at this end is a nail file 30. This is a flat blade member cut on either surface, preferably the upper surface, to form the file 31, and it may be reduced in thickness and rounded at its free end 32 to provide a means for cleaning under the nail. It is pivotally mounted on the upper side of the upper jaw member 11 by means of an eyelet 33 passing through the opening in the members 10 and 11 and rolled over at its opposite ends to form securing flanges 34. This eyelet also passes through an opening in the member 30 to form a pivotal mounting for this member to allow it to be swung in a plane substantially parallel to the plane of the members 10 and 11 to a position on the top of the upper member 11 when not in use, or to be swung laterally, as shown in dotted lines Fig. 4, to a more exposed position for use than when lying over the upper member 11. When in the position on the top of the member 11, as shown in Figs. 1 and 2, it lies under and is covered by the operating lever 23, so that it is protected and prevented from catching on clothing or other objects.

On the opposite side edges of this file member adjacent its pivot 33, it is provided with a pair of upwardly extending lugs 35 between which the free end portion of the lever may seat and be held when in the closed or inoperative position of Figs. 1 and 2, and prevent its inadvertently being swung from this position when carrying or not in use. The pivotal mounting for the file 30 is a fairly tight friction mounting so it is not loose to swing freely about the pivot, but it is tight enough for a frictional pivot so that the file is frictionally held in any position to which it may be swung, but still may be swung to any of these positions by the operator, as desired. By using a tubular eyelet for the pivot mounting of the file, the opening through the end of the device for mounting it on a key-ring or chain is maintained.

It will be seen from the above that this novel construction and arrangement comprises a nail file and cleaning element which is normally covered or enclosed by the operating lever when

in the inoperative position, and that this file in turn is provided with means for holding the lever against inadvertent movement laterally out of its closed position on the upper side of the upper jaw member, but that the lever may be readily swung to its operative position and the file may be readily exposed and swung to a position for use. The lugs 35 on the file are preferably located relatively close to the pivotal mounting for the file, and also the free end of the operating lever, so that they will have the maximum holding effect on the lever and will effectively prevent its being swung laterally out of its closed position on the top of the file member during the carrying operation.

Having thus set forth the nature of my invention, what I claim is:

1. A nail clipper of the character described comprising connected members having cutting jaws at one end normally held apart, a pivotally mounted operating lever for forcing the jaws together for the clipping operation and arranged to lie adjacent the outer surface of one of the members when in inoperative position, a file member pivoted to said latter member adjacent its other end to swing in a plane parallel to said member to and from a position on the outer side of said member under the lever, and said file member being provided with laterally spaced lugs arranged to receive the lever between them to hold it against lateral swinging movement.

2. A nail clipper of the character described comprising connected members having cutting jaws at one end normally held apart, a pivotally mounted operating lever for forcing the jaws together for the clipping operation and arranged to lie adjacent the outer surface of one of the members when in inoperative position, a file member pivoted to said latter member adjacent the other end thereof to swing to and from a position on the outer side of said member, and means on the file member to hold the lever against lateral swinging movements parallel to the plane of said member when it is in said inoperative position.

3. A nail clipper of the character described comprising connected members having cutting jaws at one end normally held apart, a pivotally mounted operating lever for forcing the jaws together for the clipping operation and arranged to lie adjacent the top surface of the upper member when in inoperative position, said lever being adapted to swing laterally, a file member pivotally connected to the other end portion of said upper member to swing in a plane parallel to said member to and from a position on the upper side of said member, and laterally spaced lugs on the file member between which the lever seats to hold it against lateral swinging movements.
